UNITED STATES PATENT OFFICE.

CHARLES SHIRLEY, OF LUZERNE, IOWA.

BAG HOLDER AND WEIGHER.

SPECIFICATION forming part of Letters Patent No. 299,863, dated June 3, 1884.

Application filed March 20, 1884. (No model.)

To all whom it may concern:

Be it known that I, CHARLES SHIRLEY, a citizen of the United States, and a resident of Luzerne, in the county of Benton and State of Iowa, have invented certain new and useful Improvements in Bag Holders and Weighers; and I do hereby declare that the following is a full, clear, and exact description of the invention, which will enable others skilled in the art to which it appertains to make and use the same, reference being had to the accompanying drawings, which form a part of this specification, and in which—

Figure 1 is a side view of a portion of the frame of a thrashing-machine, showing my improved grain bagging and weighing device in position. Fig. 2 is a top view of the same. Fig. 3 is a perspective view of the device detached, and Fig. 4 is a vertical section of the same.

Similar letters of reference indicate corresponding parts in all the figures.

My invention has relation to devices for bagging and weighing grain, and more especially adapted for thrashing-machines which travel over the field, thrashing the grain as it is taken up from the swath; and it consists in the improved construction and combination of parts of such a device, which is adapted to drop the bags of grain as they are weighed and tied, as hereinafter more fully described and claimed.

In the accompanying drawings, the letter A indicates the grain-spout, through which the grain passes from the separator into bags supported in the device, which consists of a lever, B, pivoted near its rear end upon an arm, C, projecting laterally from the rear corner of the machine-casing, and the said lever is slotted longitudinally at its forward end, as shown at D, in which slot a receptacle, E, slides and may be adjusted, which receptacle is adapted to receive weights or poises to the weight of the grain to be filled into each bag. An upright, F, having a slight inward inclination, is secured upon the rear end of the lever, and a circular plate, G, having a central upright sleeve, H, is pivoted upon the upright, and has three (more or less) upright rods, I, at its periphery, at equal distances to the upper ends of which a corresponding number of arms

J, connected at their inner ends to a small disk, K, secured to the upper end of the central sleeve, are secured. The edges of these arms are provided with rows of upright pointed pins L, upon which a portion of the edges of the bags to be filled may be hooked, the lower ends of the bags resting upon the bottom plate, and curved arms or plates M, having a row of outwardly-projecting pins, N, and having a series of perforations, O, are hinged at one end to the upper ends of the upright rods. These arms or plates reach nearly over the space between the upright rods, and overlap the ends of similarly-curved arms or plates P, hinged to the upright rods, and meeting the ends of the arms having the pins, and the outer ends of the smooth arms are provided each with an outwardly-pointing pin or lug, Q, which serves to catch and engage one of the perforations in the arms having the pins, locking the two ends of each pair of arms together. A portion of the upper edges of the bags to be filled are hooked upon the pins upon the arms, and the sides of the bags forced out until distended, when each of the locking-pins upon the smooth arms will catch in one of the perforations in the outer arms, holding the mouth of the bag distended for the reception of the grain passing out through the spout.

To hold the lower ends of the bags in place, curved arms R are hinged upon the lower portions of the upright rods, having catches upon their outer ends adapted to engage catches upon the upright rods, the arms reaching from one rod to another. The forward end of the lever is guided by a bail, S, which projects from the side of the machine-casing, and which serves to guide it rocking in a vertical plane, and to prevent it from tipping too far up or down, and the under side of the bottom plate has a number of catches, T, one for each compartment, formed by the radial arms and the upright rods, and a spring-catch, U, upon the upper side of the lever will engage one of these catches or notches upon the bottom plate, preventing the plate from revolving. An arm, V, projects from the side of the machine-casing, and will strike the spring-catch upon the lever, when the forward end of the same is tilted upward by the weight of the grain

in the bags, releasing the catch from the notch and allowing the bag-holding frame to revolve; the inclined position of the upright upon the lever and its rearward inclination, caused by 5 the tilting of the lever, causing the bag which is nearest to the side of the machine to revolve toward the rear, thus bringing an empty bag under the spout, and allowing the full bag to be tied up and removed and an empty bag to 10 be put in its place, a seat, W, being provided at the rear end of the machine for the person attending the bags.

It follows that this device may be used attached to any machine delivering grain, seed, 15 or any other dry article measured or weighed in bags—as, for instance, at an elevator, mill, or similar building—the principle of my invention remaining the same.

Having thus described my invention, I claim 20 and desire to secure by Letters Patent of the United States—

1. The combination of a lever pivoted near its end under the discharge-spout, and having a sliding weight upon its long end, an upright 25 secured in an inwardly-inclined position upon the short end of the lever, a bag-supporting frame having compartments for the bags to be filled, and turning upon the upright under the end of the discharge-spout, notched catches 30 secured under each bag-compartment, a spring-catch secured at one end upon the upper side of the lever adapted to engage the notched catches, and a laterally-projecting arm upon the machine-frame adapted to strike the free 35 end of the spring-catch when the long end of the lever is raised, as and for the purpose shown and set forth.

2. The combination of a lever pivoted near one end under the discharge-spout, and having 40 a sliding weight upon its long arm, an upright secured in a slightly inwardly-inclined position upon the short end of the lever, a bag-supporting frame pivoted upon the up-

right, having means for securing the mouths of the bags open, and having outwardly-opening doors or bars, closing the outer sides of the compartments for the bags, provided with catches closing by being forced outward by the grain in the bags, and means for holding one compartment under the grain-spout at the time, and for allowing the frame to turn when the lever is tilted by the weight of the filled bags, as and for the purpose shown and set forth.

3. The combination of a lever pivoted near 55 one end at the grain-discharging spout, and having a sliding weight upon its long arm, an upright secured in a slightly inwardly-inclined position upon the short arm of the lever, a bag-supporting frame consisting of a bottom plate, a central upright sleeve turning upon the upright, a number of uprights secured at equal distances at the edge of the bottom plate, and a corresponding number of radial arms having upwardly-pointing pins, curved arms having 60 outwardly-pointing pins at their outer ends and pivoted upon the upper ends of the uprights, adapted to meet and engage with the perforated curved arms, curved arms hinged at the lower ends of the uprights, and having 65 means for catching their free ends in catches upon the adjoining uprights, and means for holding one of the compartments formed by the uprights and the radial arms under the grain-spout at the time, and for releasing it 70 when the lever is tilted by the weight of the filled bag, allowing the frame to turn and bring a new compartment under the spout, as and for the purpose shown and set forth.

In testimony that I claim the foregoing as 80 my own I have hereunto affixed my signature in presence of two witnesses.

CHARLES SHIRLEY.
